TRUNK SUPPORT AND GUIDE

Filed June 1, 1925

Fig. 1.

Fig. 2. A perspective view of a conical device, likely a filter or strainer. The device is labeled with the following numbers:

- 1: The main conical body.
- 2: A circular opening at the base of the cone.
- 3: A small circular opening near the top of the cone.
- 4: A curved strip of material attached to the side of the cone.
- 5: A horizontal band of material near the top of the cone.
- 6: A horizontal band of material near the base of the cone.
- 7: A small circular opening near the top of the cone.
- 8: A curved strip of material attached to the side of the cone.
- 9: A horizontal band of material near the top of the cone.
- 10: A small circular opening near the base of the cone.
- 11: A small circular opening near the top of the cone.
- 12: A small circular opening near the base of the cone.

UNITED STATES PATENT OFFICE.

JOSEPH A. KILLINGER AND ANDREW W. BEAN, OF WASHINGTON, DISTRICT OF COLUMBIA.

TRUNK SUPPORT AND GUIDE.

Application filed June 1, 1925. Serial No. 34,263.

This invention relates to a support and guide designed particularly for use in connection with wardrobe trunks, and adapted to provide an independent wholly separable element on which the trunk may be supported, and on which it may be guided in the usual opening and closing, without permitting the usual trunk rollers coming into direct contact with the floor or floor covering.

Wardrobe trunks are comparatively heavy, and as known, are supported on end and on rollers or slides which rest directly upon the floor or floor covering, and which move over the latter in the opening of the trunk. With the best type of such movable support, the continued opening and closing of the trunk in the use of the latter will quickly mar the floor or wear through the floor covering. The present invention is in the nature of a wear plate, particularly designed for properly supporting the trunk, and permitting it to be opened or closed in the usual manner, with the wear strain of such movement taken by the plate and the usual marring of the floor or wear of the floor covering entirely prevented.

The wear plate of the present invention is constructed as a separate element, of general triangular shape, with means at the apex end, combined with a trunk carried element in line with the hinge, for pivotally supporting the trunk on the wear plate, the opposite end of the wear plate providing a track section on which roller supports of the trunk are adapted to travel in opening and closing the trunk section.

The invention is illustrated in the accompanying drawings, in which:

Fig. 1 is a perspective view of the improved wear plate.

Fig. 2 is a plan of the same, the wardrobe trunk being shown thereon in dotted outline.

Fig. 3 is a longitudinal section of the same, on line 3-3 of Fig. 2, a broken view of the trunk being shown in position.

The wear plate proper comprises a metallic section of general triangular form in plan, shaped to provide a central or platform section 1, which at the forward end is extended downwardly in the form of an abrupt shoulder 2, of a height approximating that of the rollers with which the trunk is supplied. In advance of the depending

portion 2, the plate is extended forwardly to provide a track section 3, the free edge of the track section, and also the shoulder portion 2, being of arcuate shape on a curve corresponding to the plane of movement 60 of the trunk rollers, as will later appear. The ends of the track section are preferably turned upwardly to form limit stops 4 to limit the opening movement of the trunk sections.

At the rear end, the plate is formed with a further downwardly extending shoulder 5, corresponding to the shoulder 2, beyond which the plate is extended rearwardly to form a bearing section 6, that portion of 70 the plate beyond the bearing section being formed in a return bend to provide a supporting section 7 in the plane of the platform section 1, the supporting section being formed with an opening 8. The trunk, indicated at 9, is formed in line with the hinges 10 with a ball extension 11, of a size to seat partly in the opening 8, and form a rotating bearing support for the trunk. The respective trunk sections are formed or provided 80 near their meeting edges on their lower sides with rollers 12, here shown as ball rollers, which, when the ball extension 11 is in the opening 8, are adapted to rest on the track 3.

With the trunk positioned on the wear plate as described, it is apparent that the co-operation of the ball extension 11 with the opening 8 in the wear plate, will pivotally support the trunk at this point, while the 90 rollers 12 at the forward portions of the sections of the trunk may be freely moved on the track section 3 of the wear plate in the opening and closing of the trunk. These rollers 12 are preferably arranged near the 95 inner edges of the respective trunk sections, so that the maximum opening of the sections is permitted before the rollers engage the limit stops 4.

If desired, and as preferred, the lower 100 surface of the track section 3 of the wear plate, and the bearing section 6, may be provided with suitable material, as rubber or the like, indicated at 13, to prevent sliding of the wear plate on the surface on which it may be placed, thus rendering the trunk and wear plate a substantial fixture when in applied positions.

The wear plate is constructed of metal of substantial thickness for the purpose noted, 110

and it is to be particularly understood that, as will be clear from Fig. 2 of the drawings, the maximum width of the plate is less than that of the trunk when closed, and that the maximum length of the plate is less than the similar dimension of the trunk. Thus the wear plate may form a desirable adjunct of the wardrobe trunk as completed for the trade, may be readily stored in the trunk until it is desired for use.

The use of the wear plate dispenses to a considerable extent with the number of supporting rollers heretofore deemed necessary to carry the weight of the trunk and permit its movement in opening and closing. In this connection, it is to be noted that with the wear plate there are but three points of support for the trunk, and that but two of these are rollers. This is a direct result of providing the wear plate with the platform section 1, which, when the trunk is positioned on the wear plate, is so close to the lower surface of the trunk as to prevent any liability of the trunk tipping when in closed position.

Claims:

1. A guide and wear plate for wardrobe trunks formed at one end with an opening to receive and support one end of the trunk, the opposite end of the plate being formed to provide a track to movably support the sections of the trunk in their opening and closing movements.

2. A guide and wear plate for wardrobe trunks formed at one end with an opening to receive a ball extension in line with the hinged connection of the trunk sections, the opposite end of the plate providing a track to receive and guide rollers carried by the movable sections of the trunk.

3. A wardrobe trunk support and guide, comprising a member of substantially tri-

angular form in plan, a trackway at the forward end of said member, a raised platform in rear of the trackway, and a supporting section in rear of the platform.

4. A wardrobe trunk support and guide, comprising a member of substantially triangular form in plan, a trackway at the forward end of said member, a raised platform in rear of the trackway, a bearing section in rear of the platform, and a supporting section overlying the bearing section.

5. A wardrobe trunk support and guide, comprising a member of substantially triangular form in plan, a trackway at the forward end of said member, a raised platform in rear of the trackway, a bearing section in rear of the platform, and a supporting section overlying the bearing section, and means carried by the trackway and bearing sections to prevent the support and guide slipping on the surface to which it is applied.

6. A guide and wear plate for wardrobe trunks, comprising an independent wholly separable section of less width and length than the similar dimensions of the trunk when closed, said section being formed at one end to support the sections of the trunk to permit their relatively hinged movement and being formed at the opposite end to support the sections of the trunk during their relatively opening and closing movement.

7. A portable wardrobe trunk support and guide, comprising a substantially triangular shaped section formed at the apex to support the trunk in line with the hinged connection between the sections and formed on the base line to guide the trunk sections in their relative movements.

In testimony whereof we affix our signatures.

JOSEPH A. KILLINGER.
ANDREW W. BEAN.
